Primary Examiner — Christian P. McLean

(74) Attorney, Agent, or Firm — Nitin Kaushik

(57) **CLAIM**

The ornamental design for a tent, as shown and described.

DESCRIPTION

FIG. 1 is a bottom perspective view of a tent, showing my new design;

FIG. 2 is a top perspective view thereof;

FIG. 3 is a usage state view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is an enlarged view of the portion indicated in FIG. 1.

(Continued)

The broken lines in the drawings illustrate the portions of the tent, which form no part of the claimed design.

1 Claim, 10 Drawing Sheets
